UNITED STATES PATENT OFFICE.

SAM PRESTON AND BEN PRESTON, OF BATLEY, ENGLAND.

MILLING AND FULLING MACHINE.

SPECIFICATION forming part of Letters Patent No. 537,170, dated April 9, 1895.

Application filed September 22, 1894. Serial No. 523,827. (No model.) Patented in Belgium May 26, 1894, No. 83,960, and in Austria July 3, 1894, No. 2,900.

To all whom it may concern:

Be it known that we, SAM PRESTON and BEN PRESTON, subjects of the Queen of Great Britain, residing at Batley, in the county of 5 York, England, have invented new and useful Improvements in Milling and Fulling Machines, (which have been patented in Belgium the 26th day of May, 1894, No. 83,960, and in Austria the 3d day of July, 1894, No. 10 2,900,) of which the following is a specification.

This invention relates to machinery or apparatus employed for "milling" and "fulling" woolen, woven, felted, or other fabrics, 15 and it has special reference to that class of machines for which Letters Patent were granted in the United States of America to William D. Baldwin, administrator of the late Benjamin Preston, the fifth day of June, 20 A. D. 1894, No. 521,126, in which the two operations of "milling" and "fulling" are performed simultaneously in the same machine by arranging the fulling stock feet to work vertically at the end of the milling machine.

25 The object of the present invention is to construct a combined milling and fulling machine with an adjustable bottom, a turn made in two or more pieces capable of being raised or lowered to or from the said adjustable bottom, said machine being provided with or without flangeless milling rollers.

In the drawings: Figure 1 is a longitudinal section of a combined milling and fulling machine embodying our improvements; Fig. 2, a 35 transverse section on line $x-x$ Fig. 1; Fig. 3, an external side elevation of machine.

A is the framework of the machine, which is made of metal in the usual skeleton form and provided with an inner lining of wood, 40 earthenware, porcelain, or the like, or two or more of these materials combined; but a lining A' of wood is more generally employed. The framework A and lining A' constitute the casing of the machine.

45 At Fig. 1 in order to avoid complicating the drawings, we have omitted to show the skeleton metal framework A in dotted lines behind the lining A'. The framework A and its lining are provided with a top or covering A² of the usual construction and material. B B' are the fulling stock feet, stepped as

shown, and arranged to work, at the rear of the milling portion of the machine, in suitable slides and between the width contracting pieces A³ A⁴ of the lining A'. The stock 55 feet B B' receive a vertical reciprocating motion from the shaft C of the machine through cranks C' C², connecting rods C³ C⁴, and blocks C⁵ C⁶ fixed as shown to the stock feet.

D D' are the milling rollers which may be 60 flangeless (or not) as shown and they are arranged at a suitable distance from the stock feet B B' within the framework of the machine, and mounted on shafts supported by pedestals or adjustable bearings arranged to 65 be fixed on or work in the said framework. The rollers are built up in parts, that is to say, two flanges d d' are provided of any suitable size and thickness. On one or both of the said flanges d d', may be cast or fixed a 70 boss d² and a ring d^{xx}. A boss is shown on each flange in the drawings. Around the boss and between the said flanges are placed, and bolted thereto, any desired number of wood segments d³, preferably four, or six, 75 made the endway of the grain. These segments are of such a thickness as to suit the diameter of the rollers, and the flanges d d' may or may not project beyond the periphery of the wood laggings or center portion of 80 the roller. They may also when required be lined or edged with a ring d^x of brass, earthenware or its equivalent to prevent them or the rollers wearing away at the edges.

Composite milling rollers D D' constructed 85 as herein described and shown may be held together by bolts d⁵ passing through the flanges d d' and secured to the shaft by keys d⁶. They may also be used in place of the rollers now employed on milling machines 90 of ordinary construction. When the flanges do not project beyond the periphery of the rollers the sides of the spout or trough E may be made to extend to or beyond the center of the rollers up to, or nearly to, the throat F 95 and the sides and bottom of the spout E may when desired be provided with an inner lining of wood, brass, earthenware, porcelain or equivalent material which may extend the whole or any portion of the length of the 100 spout. The requisite tension to the rollers D D' may be imparted thereto by flat springs

- D^x, one end of which is connected to stationary rod or fixing D^{xx} while to the opposite end is jointed a rack D^{xxx} which engages with a pinion D⁴ actuated by worm and wheel D⁵ through shaft D⁶ and hand wheel D⁷. The rollers D D' are geared together with suitable spur or other gearing D⁸, and motion is imparted to them through driving pulley D⁹. E is the spout of the machine through which the material operated upon, after passing between the milling rollers D D', passes to the fulling stock feet B B'. The spout E may be made to taper and may be provided with a lid E' jointed to the shaft of the upper milling roller D as shown and it is weighted at E² to give the requisite drag to the material passing through the spout. G is the knocking off board connected by levers in the ordinary manner with the belt slipping mechanism. H is the turn or adjustable bed, which is mounted within the framework of the machine the contracting pieces A³ A⁴ being at any suitable distance below the rear end of the spout of the machine.
- 25 The turn or adjustable bed may be mounted upon a bar H' carried in adjustable bearings H^{xx} on the framework of the machine whereby the distance between the "turn" and stock feet B B' may be increased or diminished as required. The bearings H^{xx} are carried on the ledges a of framework A and secured thereto by bolts a' arranged to slide in slot holes a². The position of each bearing H^{xx} may be adjusted by a screw a³ as shown at Fig. 3.
- 30 The turn or adjustable bed H may be made in one or more pieces of any suitable shape and length so as to extend to any required distance from under the spout to the bottom lining of the machine.
- 35 In the drawings a turn or adjustable bed is shown made in three pieces H, H², H³. The piece H² is fixed at an angle to the piece H, while the piece H³ is jointed to the piece H² so that its front end h may be raised or lowered by the chain H⁴ whenever the latter is wound or unwound on the pulley H⁵ mounted on shaft H⁶, which is rotated by worm and worm wheel H⁷ through shaft H⁸ armed with 40 a hand wheel H⁹. In order to keep the lower piece H³ to its work it is weighted at H¹⁰ as shown. The angle of the turn or adjustable bed may also be regulated by means of a bar I jointed to the piece H² and provided with 45 any desired number of holes by which it may be pinned to the cross-piece I' fixed to the lining A' of the machine.
- 50 J is a curved false bottom jointed at j to the end A^x of the machine and it works between the contracting pieces A³ A⁴. The false bottom J is capable of being raised or lowered by hand by any convenient means, such as an eccentric J' actuated by hand wheel J² and gearing J³ whenever the exit orifice H^x 55 is required to be contracted or enlarged.
- 60 K K' are the ordinary rollers for guiding the fabric.

L is a fly wheel mounted on the end of the crank shaft.

M M' are pulleys around which the belt M² 70 passes for transmitting motion to the crank shaft C and stock feet from the milling roller shaft.

By constructing the machine as herein described, there is less danger of the fabric being damaged while at the same time the combined milling and fulling operations are performed in less time and with better results.

In some cases when preferred, we arrange within the machine, say in any convenient 80 position in front of the mouth of the turn or adjustable bed H and below and beyond the milling rollers D D' one, two, or more rollers N N' for spreading or opening out the cloth or other fabric as it leaves the stock feet. 85 Any or the whole of these rollers may be armed with spiral blades or pins n arranged round the periphery or peripheries of the rollers so as to run in the same or opposite directions. These rollers may be driven by 90 the drag of the material operated upon, or by gearing or its equivalent.

Having now described the nature of our invention, what we claim, and desire to secure by Letters Patent, is—

1. The combination, substantially as hereinbefore set forth, of a casing having a contracted portion, milling rolls contained within the casing, mechanism for operating the milling rolls, means for imparting the requisite drag upon the material, reciprocating stock feet contained within the contracted portion of the casing, mechanism for operating them and an adjustable weighted bed interposed between the milling rolls and stock feet and co-operating with the stock feet, said bed being made in pieces jointed together and means for raising and lowering the weighted end of the said bed.

2. The combination of the casing having a contracted portion the milling rolls the reciprocating stock feet contained within the contracted portion of the casing of the machine the adjustable weighted bed interposed between the milling rolls and stock feet and co-operating with the stock feet, said bed being made in pieces jointed together and means for moving the upper end of said bed to and from the stock feet and means for raising and lowering the weighted end of said bed.

3. The combination of the casing the milling rolls, the reciprocating stock feet contained within the casing of the machine the adjustable weighted bed made up in pieces jointed together capable of being moved to 125 and from the stock feet at one end and raised and lowered to its work at the other end, means for raising and lowering the weighted end of the said bed, the false bottom hinged within the casing of the machine below the 130 stock feet, and means for raising and lowering the free end of the false bottom to and from the weighted end of the said adjustable bed.

4. The combination of the casing having a contracted portion the milling rolls, the reciprocating stock feet contained within the contracted portion of the casing, the tapered 5 spout interposed between the stock feet and the milling rolls, and having its larger end next the stock feet, the adjustable weighted bed made up in sections jointed together said bed being interposed between the spout and 10 stock feet, means for raising and lowering its weighted end to its work, the false bottom hinged to the casing below the stock feet and co-operating with the weighted end of the adjustable bed and the spreading out rollers interposed between the milling rolls, the adjustable bed, and the guide roller. 15

In testimony whereof we have hereunto signed our names to this specification in presence of two subscribing witnesses.
